ROLLER-TYPE WASHING OR DRY-CLEANING MACHINE

Lee B. Green, Lakewood, Ohio, assignor to The
Globe Machine & Stamping Company, Cleve-
land, Ohio, a corporation of Ohio

Application March 2, 1931. Serial No. 519,609

17 Claims (Cl. 68—38)

My invention relates to washing appliances of the general class in which agitation is effected by rotating the container which houses the clothes and the cleaning liquid.

Generally speaking, my invention aims to provide an easily operated, inexpensive and compact washing appliance of this class which will require no stand, pivoting means or crank; which can easily be operated by rolling the entire appliance as a unit on a table or bench; and which will prevent the formation of a vacuum within the appliance, without causing liquid to be splashed on the table.

More particularly, my invention aims to provide a household type of washing machine which can easily be operated by merely rolling the entire machine back and forth on a table, floor or bench; and one in which the weight of the cleansing liquid will tend to halt the rolling.

In some additional aspects, my invention aims to provide a rollable washing appliance which will be equally suitable for use with a non-wetting (or socalled dry-cleaning) liquid or with water; aims to provide such an appliance with an air inlet disposed for minimizing the ejection of liquid through this inlet, and with easily emptied drip-catching means to prevent the ejected liquid from being splashed on the table upon which the appliance is being rolled; and aims to construct such an appliance so that it can readily be set upright on a flat surface while filling or emptying it, or while boiling clothes in it.

In some further aspects, my invention aims to provide a rollable washing appliance in which the rolling portions extend radially outward of the receptacle part of the appliance, in which the outward projecting of these portions will not interfere with the use of means for tightly clamping the cover of the appliance to the said receptacle part, and in which one rolling portion will be adapted (when the appliance is set with its axis upright) to catch any liquid splashed over the mouth of the receptacle part of the container while the latter is being filled.

In a further object, my invention aims to provide a rollable washing appliance construction which will readily permit the tubular shell portion to be of a polygonal or otherwise non-circular section to increase the agitation of the contents of the appliance while the latter is being rolled, while allowing the rolling portions to be of circular or elliptical contours, and aims to provide a construction in which the edge part of a detachable cover member can readily form one of the rollable portions.

In still another object, my invention aims to provide a rollable washing appliance in which the cover portion is pressed against the receptacle portion by interposed clamping means which releasably engage parts of the cover portion, and in this aspect aims to provide appliance constructions in which the providing of the roller-affording provisions will not interfere with the convenient and effective use of such clamping means.

More particularly, my invention aims to provide an appliance of the above recited characteristics, in which the cover member has perforations through which the clamping means extend when they are operative, in which portions of the clamping means will be held in conveniently accessible inoperative positions when unlatched, and in which the providing of the said cover perforations will neither materially increase the diameter of the cover member nor materially decrease the rigidity of this member.

Still further and also more detailed objects will appear from the following specification and from the accompanying drawings, in which

Fig. 1 is a side elevation of a rollable washing appliance, showing this as it appears when in use.

Fig. 2 is an end view of the same, taken from the cover end, or from the right-hand side of Fig. 1.

Fig. 3 is a section taken along the line 3—3 of Fig. 1 but drawn on a reduced scale.

Fig. 4 is a fragmentary section taken along the line 4—4 of Fig. 2, but drawn on an enlarged scale.

Fig. 5 is an enlargement of a portion of the end view of Fig. 2, showing one of the clamping means in an unlatched disposition.

Fig. 6 is a section similar to the upper left-hand portion of Fig. 4, but showing the positions of parts of the clamping device when the clamping hook has just been released from latching engagement with the bead on the cover halted by another portion of the cover.

Fig. 7 is a side elevation of another embodiment of my invention, namely one in which one of the roller or disk-wheel portions is part of the bottom of the container, while the companion roller is formed separately from the cover member of the container.

Fig. 8 is an enlarged and fragmentary section taken longitudinally of the container along the line 8—8 of Fig. 7.

Fig. 9 is a perspective view of an embodiment generally similar to that of Figs. 1 to 6, but

having elliptical roller portions disposed with the major axes of their elliptical contours disposed in a common plane.

Fig. 10 is a perspective view of the embodiment 5 of Fig. 9, taken with the cover member of the container rotated 90 degrees about the axis of the container.

Fig. 11 is a perspective view of still another embodiment, namely one in which the receptacle portion is of generally circular section and one having only a single roller portion of larger diameter than the receptacle portion.

Fig. 12 is a section similar to a left-hand upper corner portion of Fig. 4, but showing a modified disposition of the cover-clamping means.

In the embodiment of Figs. 1 to 6 inclusive, my washing appliance included a container comprising a receptacle portion and a cover releasably clamped to the said receptacle portion, and has two disk wheel portions respectively integral with the cover and with the bottom of the said receptacle portion; this bottom being permanently secured to the shell of the receptacle portion and the bottom member (which includes one of the said disk wheel portions) being formed both for readily supporting the receptacle portion in an upright position and for catching any liquid which may be splashed over the mouth of the said shell during the filling of the container, and the cover member being constructed to permit of tightly sealing it to the mouth end of the said shell.

This tubular shell 1 is preferably of a non-circular general section, such as a square section with rounded corners, and desirably also is provided with longitudinal flutes 2 which terminate short of both ends of the said tubular part and aid in agitating the contents of the container when the latter is rotated.

Fitted into and secured to the bottom end of this shell 1 is a correspondingly shaped flange 3 which forms the periphery of the bottom 4 of the receptacle portion, and which flange connects this bottom 4 with a disk wheel portion 5 extending radially outward of the said bottom. This disk portion 5 has its peripheral part rolled into rim 6 which desirably depends partially below the said disk (as shown in Fig. 4) and is thereafter curved upwardly to form a rim of outwardly concaved cross-section. The rim formation preferably extends (in cross-section) to an arc sufficiently less than 270 degrees, so that the rim on the bottom member also constitutes an upwardly open trough for catching any liquid which may be splashed or spilled outside the shell 1 while the latter is being filled.

The upper end of the tubular shell 1 of the receptacle portion of my washing appliance is desirably flanged outwardly to afford a seat for a packing ring, as for example by rolling this upper end into a tubular annular bead 7 on which a hollow packing ring 8 is seated when the cover is attached to the receptacle portion, the inner edge of this bead being preferably flush with the bore of the shell 1.

The corresponding cover member includes a central disc 9 bordered by an upstanding annular bead 10 of inverted U-shaped section. This bead is shaped in plan view to register with the shell bead 7; and the cover bead 10 preferably has its inner flange 10A of a sufficient height so as to depend into the bore of the tubular receptacle wall 1 and of an outside diameter closely approaching that of the said bore. The cover member also includes a disk wheel portion 11 extending out-

wardly from the outer flange 10B of the said bead and having its peripheral portion rolled into a tubular cover rim 12, which desirably is of the same diameter and cross-section as the rim 5 on the bottom member.

To fasten the cover member to the receptacle portion of the container, I provide a plurality of clamping means spaced circumferentially of the container and preferably supported by relatively flat portions of the shell wall 1. As here shown, each of these clamping means includes a supporting bracket having two parallel wings 13 extending outwardly of the container from a bracket plate 14 bearing against (and welded to) the outer face of the said wall. Pivoted upon a horizontal pin 15 spanning the wings 13 is a forked lever 16 which includes a normally depending handle 16A. Spanning the arms of this forked lever 16 and below the said pin 15 when the cover is latched to the receptacle portion is a second horizontal pivot pin 17, upon which the lower end of a hook member 18 is pivoted. This hook member extends through a perforation 19 in the disk wheel portion 11 of the cover and has its upper end recurved towards the receptacle to 100 form a hook 18A, after the manner disclosed in my copending application #507,338, filed January 8, 1931 on a container closure.

To cooperate with this latching hook, I provide a keeper 20 formed from the metal of the 105 disk wheel portion 11 adjacent to the inner edge of the perforation 19 and extending upwardly at a short distance from the adjacent portion of the outer wall 10B of the bead on the cover member, so that this keeper together with the 110 said portion of the outer bead wall will constitute a latching trough into which the free end of the hook 18A will depend (as in Fig. 4) when the hook member is forced downward by swinging the lever 16 from the raised position of Fig. 6 115 to the depending position of Fig. 4.

The width (radially of the cover member) of each perforation 19, through which a hook member 18 extends when the cover member is attached to the container, is preferably such that 120 the outward edge 19A will be engaged by the hook member when the latter has been swung (as in Fig. 6) so that its center of gravity is farther outward from the adjacent portion of the receptacle wall 1 than the pin 17 on which 125 the hook member is pivoted, thereby causing gravity to hold each hook member in a released position while the other hook members are being released. This hook-halting arrangement also 130 facilitates the attaching of the cover member to the receptacle, as each hook member 18 can readily be guided loosely through the corresponding perforation to permit the cover member to be seated, after which the hook members are 135 consecutively swung over the said latch troughs and depressed by the levers 16 connected to them.

The number of latching means employed for this purpose may obviously vary, and when the receptacle has a generally polygonal section, each of the latching means is desirably opposite the 140 middle of one of the receptacle sides, where such a side has the greatest spacing (radially of the container) from the periphery to the cover and hence provides ample room for the corresponding disk perforation 19. This permits the corner 145 portions of the cover bead 10 to extend close to portions of the cover rim 12, as shown in Fig. 2, so as not to require an undesirably large diameter for this rim.

When the cover member has thus been latched 150

to the receptacle member after the clothes and the cleaning liquid were disposed in the receptacle, the assembled container can readily be tipped on its side, and can be rolled back and forth on the top of a table 40 or the like. During this rolling, the cleaning liquid 21 and the clothes 22 (Fig. 3) are tossed about, owing to the non-circular general section of the receptacle and also to the auxiliary flutes 2, so as to cause the liquid to swish back and forth through the garments. This rolling can easily be effected manually, so that no crank arrangement or other auxiliary provisions are required. Furthermore, my washing appliance requires no supporting or pivoting stand; thereby saving both the cost of such a stand and of the crank usually required for a rotary washing appliance and also considerably reducing the packing and storage space occupied by an appliance of a given capacity.

By providing the cover member with perforations through which the hook members can extend, I permit these members to be disposed within the periphery of the rim 12 of the cover member, so that no part of the cover-clamping means will interfere with the rolling of the appliance. And by disposing each of the hook members in one of the widest portions of the cover disk portion 11, I also can readily position each of the clamping means so far radially inward of the cover rim 12 as not to be engaged by a hand grasping or otherwise manipulating that rim during the washing operation.

If hot water is used for the washing, the gradually cooling of this water would reduce its volume, thereby producing a partial vacuum in the container. Consequently, if the container were entirely sealed, the higher pressure of the outer air would prevent an easy manual detaching of the cover member after the container has again been set upright and the latching hooks have been released. To prevent the formation of such a vacuum, I provide a suitable vent, preferably disposed where the water is least likely to be splashed through it, and also provide an easily emptied drip-catching receptacle for receiving any water or suds which may still issue through the vent. Furthermore, I desirably provide means within this drip-catching receptacle for preventing the collected drip from being splashed out of the drip-catching receptacle during the rolling of the appliances.

For these purposes, I preferably provide the cover member with an axial vent port 23 opening into a vent receptacle which has one wall formed by the central part of the cover portion 9, and which has its remaining wall portions formed by a cup-like drip-catching member 24 disposed in axial alignment with the vent port 23, this cup-like member being secured at its mouth to the said central cover portion. Then I provide the cup back of this member 24 with a central aperture 25 which may be many times larger in diameter than the bore of the vent port 23, and partly fill this member 24 with a loose moisture-absorbent material 28, such as felt.

Since it is customary in rotary washing appliances to use a quantity of liquid corresponding to considerably less than half the capacity of the container, the bulk of the liquid 21 will usually be below the axis of the appliance (as will be evident from Fig. 3), and hence below the vent port 23, when my appliance is being operated by rolling it upon a table or other horizontal surface. With this vent port disposed in a

flat cover portion 9 disposed in a plane at right angles to the axis of the container, as here shown, any liquid tossed up adjacent to the cover will tend to flow both upward and downward freely past the vent port. Consequently, only quite trivial quantities of liquid will issue through this port during each use of my machine into the drip-catching receptacle, and the liquid can readily be drained out of this receptacle by merely inverting the detached cover member over a sink or wash-basin. So also, if any liquid has been spilled over the mouth of the receptacle while the latter was being filled, this will be caught by the trough of the basal rim 5 instead of flowing down upon the table, sink or other support on which my machine is being used.

In practice, I preferably make the drip-catching receptacle of less height (when the appliance is upright as in Fig. 4) than the extreme height of the cover bead 10 above the main cover portion 9, thereby permitting the cover to rest firmly on this cover bead when inverted upon a table or sink.

However, while I have heretofore described my washing appliance in an embodiment in which one of the wheel-like rims is integral with the cover portion of the appliance, and in which both rims have circular contours, I do not wish to be limited to these or other details of the construction and arrangement thus disclosed, since many changes may be made without departing either from the spirit of my invention or from the appended claims.

For example, at least one of the disk wheel parts of my machine might be separately formed from the parts which constitute the liquid container. Thus, Figs. 7 and 8 show an embodiment of my invention in which the peripheral portion of the cover is formed into a trough 10C extending entirely around the outer cover bead 10B and adjacent to that wall, into which troughs the clamping means hook after the manner shown in my said copending application. In this embodiment, one of the disk wheel rims 5 is on the bottom member as in Fig. 1, while the companion rim 26 is on the outer edge of a perforated disk 27, which is formed separately from the cover member, has at its inner edge a flange 28 secured to the peripheral shell 29. In this case, the clamping members do not extend through any other parts, but are disposed between the cover member and the said disk 27; but the auxiliary wheel-forming part also extends considerably further (radially of the container) than each of the clamping means, so that these means will not engage the surface on which the appliance is being rolled and also will not readily be engaged by the hands of the person who is rolling the appliance.

Fig. 9 shows an embodiment in which the roller-like rims 30 and 31 are respectively formed on the cover and the bottom of a container which also has an unindented shell portion 32. Each of these rims is of an elliptical contour, the major axes of these ellipses being in a common plane extending through the axis of the container. When this appliance is rolled, the elliptical curvature of its roller portions will cause the receptacle portion to be raised and lowered during each half revolution of the roller-like rims, thereby augmenting the agitation of its contents.

With the cover member attached as in Fig. 9, the appliance there illustrated would roll back and forth in a straight path; but the same cover

member may be attached with the major axes of the elliptical rims are in planes at right angles to each other, as in Fig. 10, so that a rolling of the machine will also tip the axis of the container back and forth. With the embodiments of both Fig. 9 and Fig. 10, the elliptical contour of the rims will tend to halt the rolling whenever one of the rims has its major axis horizontal, thereby deterring it from rolling off a table if propelled violently. However, I have found in practice, that a peripheral receptacle wall of generally polygonal section when coaxial with rims of circular contour will also have a considerable tendency toward halting whenever one of its longitudinal edges is at the bottom, so that I preferably make the roller rims of my appliance of the more cheaply manufactured circular contours.

Figs. 9 and 10 also show the use of clamping hooks 32 which hook over the cover beads 10, as I do not wish to be limited to the providing of separately formed keepers 20 (as shown in Figs. 4, 5 and 6) for engaging the hook portions of the latching means.

Nor do I wish to be limited to the providing of two container portions which extend radially of the container for considerable distances beyond the shell of the receptacle portion. Thus, Fig. 11 shows an embodiment in which the bottom 33 does not project beyond the receptacle shell 34, while the cover member and the clamp means are similar to those of Figs. 1 and 2, except (as will be obvious without further illustration) that the cover bead would be of circular contour. With this embodiment, the supporting surface 40 will be engaged by the bottom end of the shell 33 and by the cover rim 12, and the appliance will roll in an arcuate path.

So also, I do not wish to be limited to the use of cover-clamping means which operate through perforations in the cover member. For example, with a lever and hook clamping mechanism of the same general type as that shown in Figs. 1 and 4, the cover member may have the keeper portions 36 disposed below its disk wheel portion 11, forming downward extensions 37 on the outer wall of the cover bead, as shown in Fig. 12. This will permit the hook members 18 to be disposed entirely below the cover member in the upright appliance at all times.

Since any of the here illustrated embodiments of my invention can easily be rolled manually back and forth on any flat horizontal surface, my appliance with its integral wheel rim or rims is entirely self-contained, and is particularly suited for use with so called dry-cleaning or non-wetting liquids, as for example naphtha or mixtures of naphtha with other ingredients, since such liquids can be employed cold.

However, when mittens or the like protect the hands of the user, my appliance can also be employed effectively with hot water and soap flakes or the like, and with such washing liquids the clothes can be boiled in the appliance. Such boiling is facilitated by my constructing the bottom member so that in the upright container the bottom-forming portion 4 of the receptacle will be raised above the disk-wheel portion 5, thereby forming a chamber below the said bottom portion 4 which permits my appliance to be used more advantageously over a gas burner.

I claim as my invention:

1. A washing appliance comprising a tubular shell, a bottom member and a cover member respectively fitted to the two ends of the shell, each

of the said members being of larger diameter than the said shell and coaxial with the latter and having its outer end rolled into a rim formation; the rim formation on the bottom member having an annular opening directed toward the cover member so that this rim formation serves as a splash-catching trough when the axis of the shell is upright.

2. A washing appliance comprising a tubular shell, a cover detachably secured to one end of the shell, and a bottom permanently secured to the other end of the shell, the bottom being of larger diameter than the shell and having its peripheral portion rolled to form a bead of arcuate section open toward the cover end of the shell so as to form a splash-catching trough when the appliance is set upright.

3. A rollable washing appliance comprising a can-like receptacle, and a cover member releasably attached to the mouth end of the receptacle, the cover member having an outwardly directed bead registering with the mouth end of the receptacle and having its peripheral portion extending radially outward from the said bead, and the bottom of the receptacle having a peripheral extension projecting radially outward from the receptacle and of the same exterior diameter as the peripheral portion of the cover.

4. A rollable washing appliance as per claim 3, including plural clamping means each interposed between the cover member and a side portion of the receptacle and each extending through the portion of the cover member which extends radially outward from the said bead.

5. A rollable washing appliance comprising a can-like receptacle, a cover member fitted to the mouth of the receptacle, and clamping means extending alongside the receptacle for releasably latching the cover member to the receptacle, the cover member extending to a greater distance than the latched clamping means does from the axis of the receptacle so as to hold the clamping means out of contact with a surface upon which the closed receptacle is rolled.

6. A rollable washing appliance comprising a can-like receptacle, a cover fitted to the mouth of the receptacle, and plural clamping means extending alongside the receptacle for releasably latching the cover to the receptacle, the cover extending to a greater distance than the latched clamping means does from the axis of the receptacle so as to hold the clamping means out of contact with a surface upon which the closed receptacle is rolled, the cover having perforations through which the clamping means extend when latching the cover to the receptacle.

7. A rollable washing appliance comprising a can-like receptacle, a cover fitted to the mouth of the receptacle, and plural clamping means extending alongside the receptacle for releasably latching the cover to the receptacle, the cover extending to a greater distance than the latched clamping means does from the axis of the receptacle so as to hold the clamping means out of contact with a surface upon which the closed receptacle is rolled, the cover having perforations through which the clamping means extend when latching the cover to the receptacle, each of the perforations having its outward edge disposed for halting a portion of the clamping means in an unlatched disposition.

8. A washing appliance comprising a tubular shell, a cover member detachably secured to one end of the shell, and a bottom permanently secured to the other end of the shell, the bottom

- having its central portion spaced inwardly of the shell from the adjacent end of the shell, the cover member and the bottom being of counterpart diameters larger than the diameter of the shell; 5 and clamping means operatively interposed between the shell and the cover member and normally disposed within a cylindrical surface which includes the peripheries of both the bottom and the cover member.
- 10 9. In a rollable washing appliance, a tubular shell presenting a plurality of substantially flat sides; a bottom member secured to one end of the said shell; a cover member having an outwardly directed annular bead registering with the other end of the shell, the cover member extending radially of the shell beyond the said bead and having its periphery formed to form a rim adapted to roll on a flat surface; and plural clamping means operatively interposed between the shell 15 and the cover member, the clamping means being respectively adjacent to the sides of the shell and projecting when in their operative positions to a shorter distance from the axis of the shell than the radius of the said rim.
- 20 10. In a rollable washing appliance, a tubular shell presenting a plurality of substantially flat sides; a bottom member secured to one end of the said shell; a cover member having an outwardly directed annular bead registering with the other end of the shell, the cover member extending radially of the shell beyond the said bead and having its periphery formed to form a rim adapted to roll on a flat surface; the cover member having hook-engaging portions positioned radi- 25 ally outward of the cover with respect to the said bead on the cover; and plural clamping means mounted on the shell and each including a hook-member adapted to engage one of the said hook-engaging portions.
- 30 11. A rollable washing appliance comprising a can-like receptacle, a cover member normally closing the mouth of the receptacle and of larger diameter than the said mouth and having a continuously curved periphery, the cover member being provided with perforations disposed radi- 35 ally outward of the receptacle; and clamping means each including a part mounted on the receptacle and another part normally extending through one of the perforations in the cover member and hookingly engaging a portion of the cover member.
- 40 12. In a rollable washing appliance, tubular shell having its bore of substantially polygonal cross-section, and a bottom member secured to one end of the said shell, and a cover member having an outwardly directed annular bead regis- 45
- tering with the other end of the shell, the cover member extending radially of the shell beyond the said bead and having its periphery formed to form a rim adapted to roll on a flat surface, the cover member being provided with perforations disposed outward of the said bead thereon, and clamping means operatively interposed between the cover member and the shell and each extending normally through one of the said perforations. 50
13. A washing appliance comprising a container having counterpart peripherally curved portions spaced longitudinally of the container and projecting radially of the container beyond other parts of the container, upon which portions the container is adapted to be rolled back and forth; one end of the container having a substantially axial air port; and a drip-catching chamber projecting from the said end of the container, into which chamber the said port leads, the said chamber having in its outward wall an opening axial of the container and larger than said port. 55
14. A washing appliance comprising a can-like receptacle and a cover member releasably attached to the mouth end of the receptacle, the cover member having therein a chamber connected to the interior of the receptacle by an air port and connected to the outer air by an opening considerably larger than the said port, the said port and opening being both coaxial with the receptacle. 60
15. A washing appliance as per claim 14, including an absorbent member disposed within the said chamber.
16. A washing appliance comprising a can-like receptacle, a cover member fitted to the mouth of the receptacle, the cover member being formed so that the central portion of the cover member is disposed below the mouth end of the receptacle; and a cup-shaped drip-receiving member having its mouth portion attached to the outer face of the said central portion of the cover and having a perforation in its cup bottom, the cover member having a substantially axial air port leading from the interior of the receptacle to the interior of the said member. 65
17. A washing appliance comprising a can-like receptacle and a cover member releasably attached to the mouth end of the receptacle, the cover member having therein a chamber communicating with the interior of the receptacle by an air port and communicating with the outer air by an opening, the said port and opening being both coaxial with the receptacle. 70
